UNITED STATES PATENT OFFICE.

PAUL LOUIS TOUSSAINT HÉROULT, OF LA PRAZ, FRANCE.

NAVIGATION.

No. 855,510.

Specification of Letters Patent.

Patented June 4, 1907.

Application filed September 27, 1905. Serial No. 280,311.

To all whom it may concern:

Be it known that I, PAUL LOUIS TOUSSAINT HÉROULT, a citizen of the Republic of France, residing in La Praz, Savoie, France, 5 have invented certain new and useful Improvements in Navigation, of which the following is a specification.

In my application for patent No. 265,757, filed June 17, 1905, I have described a process and apparatus for navigation which utilizes the resistance of water to rapid blows or impulses upon its surface, the water acting substantially as a solid, and the impulses being of such force and so distributed 15 that the reaction will support a body of desired weight entirely above the surface of the water; so that the said body shall move forward with no more resistance than is experienced in moving through the air.

20 In order to provide a large area bearing upon the surface of the water, it is proposed in said former application to utilize a wheel with pivoted blades striking the water in rapid succession, or a wheel of such large diameter as to provide a sufficient bearing area.

According to the present invention, in place of the mechanism before proposed, I utilize a belt the lower side of which runs upon the surface of the water and is of ample 30 area, while the ends, that is to say, the portions extending around the driving wheels or pulleys, may be made of comparatively little height.

The accompanying drawings illustrate an 35 embodiment of the invention.

Figure 1 is a side elevation of the supporting device; Fig. 2 is a longitudinal section of the belt; Fig. 3 is a longitudinal section of another style of belt; Fig. 4 is a plan of a portion of the belt shown in Fig. 3; Fig. 5 is a plan of the belt and driving pulleys; Fig. 6 is a side elevation of the rear end thereof; Figs. 7 and 8 are diagrams illustrating in plan and side elevation respectively the arrangement 45 of the driving mechanism.

The body of the "boat" carries the two shafts A and B, and suitable mechanism for rotating either or both said shafts, as will be understood. Driving pulleys or drums C 50 and D are carried by said shafts, and carry a belt E the lower side E' of which provides a surface which bears upon the water and supports the boat. The side E' of the belt will naturally take an upward curve between the 55 pulleys C and D, and the shape of this curve may be regulated by means of guide rollers F.

The measure of the upward reaction of the water is the vertical component G of the normal pressure H exerted by the belt, and it is desirable to make this as great as possible by 60 making the pressure H as nearly vertical as possible. Consequently the direction in which the successive points of the belt strike the water at the point J, should be as nearly horizontal as possible. For this purpose 65 when a single drum is employed, as described in my previous application, the drum is necessarily made very large, and is consequently expensive to construct and operate. It will be understood that in order to present a sufficient surface to the water, the drum must touch the water not only along the mathematical line of contact, but over a substantial portion of its circumference. A belt, by providing between the two pulleys a considerable area, avoids the necessity which exists with a single drum, of the drums entering the water to provide the necessary bearing area. 70 Consequently with a belt there is substantially no depression in the water, and the 75 drums C and D may be made of quite small radius, so that the entire apparatus is more compact than would be a single drum. It is likewise more advantageous than the flying paddle wheels of my previous application for 80 patent, as such paddle wheels are difficult to maintain well lubricated because of the strong centrifugal force acting, and for other reasons.

The required velocity and force or pressure may be most conveniently obtained by 90 means of the gasoline type of engines commonly used in "automobile" boats, or by the still lighter engines designed for flying machines. Such engines weigh from 1 to 1½ 95 kilos per horse-power, and I have found that a 70 pound boat may be made to skim the water in the manner described and at a rate of 30 miles per hour with a 4 horse-power engine. For example, referring to Figs. 7 100 and 8, four belts E may be provided arranged at opposite sides, two near the bow and two near the stern of the hull, and each belt having its driving shaft A in line with that on the opposite side of the hull and driven from a 105 common differential gear S with the usual or any suitable controlling devices (not shown); the differential gears being driven from any intermediate gearing typified by the large gear T mounted directly on the crank shaft 110 of the two-cylinder gasoline engine U.

In order to prevent the water from clinging

ing to the belt on the upgoing side of the pulley D and thus retarding its movement, it is preferably made with a number of apertures, such for example as K (Fig. 2), through 5 which air may enter in the manner indicated by the arrows to break the suction and permit the water to run off readily.

The belt may be of a great variety of constructions in detail. A suitable construction is illustrated in Figs. 3 and 4. A series of links L are connected in staggered positions upon pivots formed by means of steel cables M surrounded by rubber N. The rubber permits a certain amount of yielding, and 15 being in a position to receive only compressive stresses, will last for a long time. The cables are well protected also by the rubber.

The spaces between adjacent links of the same line may serve the purpose of the 20 spaces K in Fig. 2. It will be advantageous, however, to close these openings over so much of the belt as is in the operating position, that is, constituting the lower side E'. For this purpose a number of flaps O of 25 leather or similar material, and the rear end of each overlapping the front end of the next, may be attached to the lower portions of the links L. When the belt runs around the upgoing side of the pulley D, the ends of the 30 flaps O will be separated from each other so as to permit access of air to free the water.

As the boat moves forward, the water has a backward movement relatively thereto which may be represented by the arrow P in 35 Fig. 1. The belt in order to have any propelling effect upon the boat, must move backward with a velocity greater than the velocity P. The movement of the belt is represented by the arrow P'. It is not essential, 40 however, to propel the boat from the belt. Separate propelling means may be provided; for example, paddles may be arranged on the rear drum D. These paddles are preferably provided with axial portions Q which perform the actual work of propulsion, and with 45 shields R lying in planes transverse to the axis, and on the inner side of the paddles Q so as to prevent splashing of water upon the belt.

The belt is shown of elongated shape, but 50 may be made of any proportions; and great width is desirable in order to hinder the escape of the water in a later direction from under the belt.

Though I have described with great particularity of detail certain embodiments of the invention, yet it is not to be understood that the invention is limited to the specific 55 embodiments disclosed.

Various modifications in detail and in the arrangement and combination of the parts, 60 may be made by those skilled in the art, without departure from the invention.

What I claim is:—

65 1. Means for supporting a body above the

surface of the water, comprising a belt presenting a large area to the water, and means for moving the belt over the water with velocity and force sufficient to cause the water to react as a solid sufficiently to support the 70 body.

2. Means for supporting a body above the surface of the water, comprising a belt E, end pulleys C and D, guide pulleys F for regulating the position of the belt between the pulleys C and D, and means for moving the belt over the water with velocity and force sufficient to cause the water to react as a solid sufficiently to support the 75 body.

3. Means for supporting a body above the 80 surface of the water, comprising a belt presenting a large area to the water, and means for moving the belt over the water with velocity and force sufficient to cause the water to react as a solid sufficiently to support the 85 body, said belt being provided with a number of apertures through which air may enter to permit the water to run off readily at the upgoing end of the belt.

4. Means for supporting a body above the 90 surface of the water, comprising a belt presenting a large area to the water, and means for moving the belt over the water with velocity and force sufficient to cause the water to react as a solid sufficiently to support the 95 body, said belt comprising a series of links pivoted together in staggered positions.

5. Means for supporting a body above the 100 surface of the water, comprising a belt presenting a large area to the water, and means for moving the belt over the water with velocity and force sufficient to cause the water to react as a solid sufficiently to support the body, said belt comprising a series of links pivoted together in staggered positions and 105 mounted yieldingly upon the pivots.

6. Means for supporting a body above the 110 surface of the water, comprising a belt presenting a large area to the water, and means for moving the belt over the water with velocity and force sufficient to cause the water to react as a solid sufficiently to support the body, said belt comprising a series of cables 115 M covered with rubber N and forming pivots, and a series of links L arranged in staggered positions upon said pivots.

7. Means for supporting a body above the 120 surface of the water, comprising a belt presenting a large area to the water, and means for moving the belt over the water with velocity and force sufficient to cause the water to react as a solid sufficiently to support the body, said belt being provided with a number of apertures for permitting the water to run off readily at the upgoing end of the belt, and means for closing said apertures over the lower side of the belt and opening them upon the upgoing end.

8. Means for supporting a body above the 125 surface of the water, comprising a belt pre- 130

senting a large area to the water, and means for moving the belt over the water with velocity and force sufficient to cause the water to react as a solid sufficiently to support the body, and additional means for propelling the body.

9. Means for supporting a body above the surface of the water, comprising a belt carried upon pulleys and means for moving the belt over the water with velocity and force sufficient to cause the water to react as a solid sufficiently to support the body, and means for propelling said body comprising paddles carried by one of said pulleys.

10. Means for supporting a body above the surface of the water, comprising a belt car-

ried upon pulleys and means for moving the belt over the water with velocity and force sufficient to cause the water to react as a solid sufficiently to support the body, and means for propelling said body comprising paddles Q on the end of one of said pulleys, and having shields R for preventing the splashing of the water inward upon the belt.

In witness whereof, I have hereunto signed my name in the presence of two subscribing witnesses.

PAUL LOUIS TOUSSAINT HÉROULT.
